United States Patent Office.

LEROY A. GLEASON, OF SOUTHBURG, CONNECTICUT.

Letters Patent No. 72,478, dated December 24, 1867.

IMPROVEMENT IN MACHINE FOR FOLDING SHEET METAL.

The Schedule referred to in these Letters Patent and making part of the same.

TO ALL WHOM IT MAY CONCERN:

Be it known that I, LEROY A. GLEASON, of Southington, in the county of Hartford, and State of Connecticut, have invented a new and improved Folding-Machine; and I do hereby declare that the following is a full, clear, and exact description thereof, which will enable others skilled in the art to make and use the same, reference being had to the accompanying drawings, forming part of this specification, in which—

Figure 1 is a plan or top view of my improved folding-machine, partly in section.

Figure 2 is a side elevation of the same.

Figure 3 is an end elevation of the same.

Figure 4 is a sectional elevation of the same, the plane of section being indicated by the line xx , fig. 2.

Figure 5 is a similar view, the plane of section being indicated by the line yy , fig. 2.

Figure 6 is a similar view, the plane of section being indicated by the line zz , fig. 2.

Similar letters of reference indicate like parts.

This invention relates to machines for folding sheet metal, and consists in the combination of the hinged frame, folding-bars, and a rock-shaft, provided with cams operating upon the upright arms of the movable folding-bar, by which the latter is advanced toward or withdrawn from the stationary folding-bar for the purpose of making a sharp or round bevel; and it consists, further, of the arrangement of the movable folding-bar hinged to the bed-plate by suitable arms, having rollers which press upon the cams of the rock-shaft, and hinged frame supporting uprights, which connect with the plate for clamping the metal to be folded, as will be herein-after more fully described.

A represents a bed-plate, which is made of cast iron, or of any other suitable material, and upon which all the other parts of this machine are arranged. At either end of the plate is arranged a post, B, as shown, which supports the pins a of the folding-bar C, proper bearings being arranged in the posts B for the pins a to revolve. This bar is, as shown in figs. 4, 5, and 6, provided with a sharp turning-edge, which coincides with the centre of the pins a , so that as the bar is turned, by means of a lever, b , into the positions indicated in figs. 5 and 6, the folding-edge of it will never change its position. At the ends of the bar C, between it and the pins a , are arranged disks, c , against which the friction-rollers d , which are arranged on a hinged frame, D, press. This hinged frame consists of two elbow-arms, d' which are pivoted to the bed-plate A, as shown, and which are connected by a rod, d'' , which turns free in its bearings in d' . To two pins, which project from the rod d'' , are hinged two upright rods, e , which are, by means of screws or otherwise, secured to the plate E, as is shown more particularly in fig. 4. This plate E is secured to the horizontal rear bar F'' of the stationary folding-bar F, by means of three or more screws, f , or otherwise, in such a manner that it may have a little play up and down with the bar F''. The disks e are provided each with a small recess, shown more particularly in fig. 3, and this recess fits over the friction-roller d , as seen, while the bar C is down, or in position shown in figs. 3 and 4, that is, when the machine is ready to receive the sheet metal for folding. The metal (shown in red lines in figs. 4, 5, and 6,) is placed between the front edge of the plate E and the upper edge of the bar F (see fig. 4) into the machine.

As soon as, by means of the lever, the folder C is turned, the recess in the disk c is moved away from the friction-roller d , and the full periphery of the disk, coming in contact with the same, presses the friction-roller, and consequently also the rod d'' down. The latter being connected by means of the rods e with the plate E, the said plate is also pulled down as soon as b is turned, and thus the metal between E and F is firmly clamped and held. As soon as the folder C is in the position indicated in fig. 6, the fold is completed and the lever b brought back into the position shown in figs. 3 and 4, when the recess in c will again come over d , and the plate E will then be raised by means of a pin, f' , on each disk, (fig. 1,) so as to release the sheet. An adjustable feed is also provided to arrange the length of the overlap, that is, to regulate how far the metal can be inserted in the stationary folder. This feed consists of a toothed bar, G, which is moved forward or backward at will by a set-screw, g . This bar G is hinged to another bar, g' , the latter being operated directly by the set-screw. The bar g' is guided at the ends by means of rods g'' , which are pivoted to the front plate of F, as shown more particularly in fig. 5. The teeth in the bar g fit into recesses in the front bar F' of the folder F, as shown in fig. 1, in such a manner that they always rest upon F', and the bar G is always thrown up by means of a spring.

h, fig. 5, so that the upper surface of the teeth may rest against the plate *E*. Thus, by moving the set-screw *g* forward or backward, a smaller or larger fold is effected. The front plate *F'* of the stationary folder *F* is, by means of two or more arms *i*, in front, pivoted to two or more uprights *i'*, which are arranged on the plate *A*. At the rear it is also provided with two arms, *K*, to the lower ends of which are arranged friction-rollers *K'*, while to their upper end is pivoted the horizontal plate *F''* of the folder *F*, to which the plate *E* is secured, the aforesaid up-and-down movement of the said plate being permitted by these pivots. The friction-rollers *K'* rest upon cams *l*, which are secured to the ends of a horizontal shaft, *H*, as seen in the drawings. By means of a handle, *m*, this shaft can be turned, and thus the whole folder *F* and all its appendages are thrown more or less forward the more the cams raise the rear end of the arms *K*, the whole folder *F*, in this case, turning on the pins *i''*, by which it is pivoted in front. When the handle *m* is being turned down, it is evident that the rod *d''* must be turned on account of its connection, *e*, with the folder *F*. For this purpose a pin, *n*, on the shaft *H*, presses upon the end of an arm, *o*, which is secured to the rod *d''*, and so the rod is turned as much as necessary to let the rods *e* come down sufficiently. The rods *e*, when the folder *F* is turned up by the eccentrics, pull the rod *d''* around sufficiently without using any other device for the purpose. The nearer the folder *F* is brought to the folding-edge of the folder *C*, the sharper will be the turn in the bent metal, and the further off, the more round will be the turn.

What I claim as new, and desire to secure by Letters Patent, is—

1. The combination of the folding-bars *F G*, disk *c c'*, frame *D*, rod *H*, cams *l*, and arms *K*, operating as described, for the purpose of making a round or sharp bend, substantially as herein set forth.
2. The combination of the folding-bar *F*, hinged arms *K*, hinged frame *D*, upright rods *e*, secured to the plate *E*, rod *H*, cams *l*, and arm *o*, all operating as described, for the purpose of clamping the metal to be folded, as and for the purpose specified.

LEROY A. GLEASON.
